(57) **CLAIM**

Applicant claims the ornamental design for a dust extractor, as shown and described.

DESCRIPTION

FIG. 1 is a first side elevational view of a dust extractor of Applicant's design in a first position;

FIG. 2 is a second side elevational view thereof, the second side being opposite the first side;

FIG. 3 is a third side elevational view thereof;

FIG. 4 is a fourth side elevational view thereof, the fourth side being opposite the third side;

FIG. 5 is a top plan view thereof;

FIG. 6 is a perspective view thereof;

FIG. 7 is a first side elevational view of the dust extractor of Applicant's design in a second position whereby a portion is pivoted relative to that shown for the first position;

FIG. 8 is a second side elevational view thereof in the second position, the second side being opposite the first side;

FIG. 9 is a third side elevational view thereof in the second position;

FIG. 10 is a fourth side elevational view thereof in the second position, the fourth side being opposite the third side;

FIG. 11 is a top plan view thereof in the second position; and,

FIG. 12 is a perspective view thereof in the second position. The broken lines depict portions of the dust extractor that form no part of the claimed design.
